UNITED STATES PATENT OFFICE.

JOHN SELLERS BANCROFT AND MAURITZ C. INDAHL, OF PHILADELPHIA, PENNSYLVANIA, ASSIGNORS TO LANSTON MONOTYPE MACHINE COMPANY, OF PHILADELPHIA, PENNSYLVANIA, A CORPORATION OF VIRGINIA.

TYPE-CARRIER FOR TYPE-CASTING MACHINES.

1,149,174.

Specification of Letters Patent. Patented Aug. 10, 1915.

Application filed November 14, 1914. Serial No. 872,219.

To all whom it may concern:

Be it known that we, JOHN SELLERS BANCROFT and MAURITZ C. INDAHL, citizens of the United States, residing at Philadelphia, in the county of Philadelphia and State of Pennsylvania, have invented certain new and useful Improvements in Type-Carriers for Type-Casting Machines; and we do hereby declare the following to be a full, clear, and exact description of the same, reference being had to the accompanying drawings, forming part of this specification, and to the figures of reference marked thereon.

15 This invention relates to improvements in type casting machines and for the purposes of the present application will be described in its embodiment in a Lanston monotype casting machine, a good illustration of which is found in United States Letters Patent No. 625,998, granted to J. S. Bancroft, under date of May 30, 1899.

Inasmuch as the construction of the machine in its general features is well understood and may be readily ascertained by reference to the aforesaid patent, it has been deemed necessary to illustrate in the present application only so much of the machine as will enable those skilled in the art to understand the construction and mode of operation of the type carrier forming the subject matter of this application.

In the accompanying drawings, Figure 1 is a top plan view of a portion of the machine in the immediate vicinity of the mold, this view corresponding to a part of Fig. 56 of the aforesaid patent with the present invention embodied therein. Fig. 2 is a perspective view of the complete type carrier removed from the machine. Fig. 3 is a side elevation. Fig. 4 is a section taken horizontally through the type carrier on a line indicated at 4-4 in Fig. 3, but with certain of the internal parts in plan. Fig. 5 is a section in a vertical plane longitudinally of the carrier, with parts in elevation, this view also showing the fixed inclines for operating the type support lever. Fig. 6 is a perspective view of the clamping member and type support removed from the carrier. Fig. 7 is a perspective view of the inclines or fixed cam surfaces for operating the support. Fig. 8 is an elevation of the same,

looking at the left hand side of the structure as shown in Fig. 7.

Like reference characters indicate the same parts in all the figures.

By reference to Fig. 1 certain of the salient features of the machine will be recognized, and for the purpose of easy identification in the drawings of the patent hereinbefore referred to, they are designated by reference numbers corresponding to the reference numbers of said patent as follows:—1 and 2 are the blocks forming the side walls of the mold; 3 is the cross blade; 4, the mold blade; 247 the link which connects the type carrier with its actuating lever for operating the carrier and cross blocks; 259, the ejector blade; 262 and 263, the blocks which form the type channel into which the type is transferred from the carrier by the ejector blade; and 275 indicates the line carrier arms for transferring assembled lines to the galley mechanism.

The type carrier of the present invention is at one end pivotally connected with the link 247 and at the opposite end is connected with the cross block 3 by a hook-like connection 248. It is adapted to be reciprocated so as to transfer a type ejected from the mold by the mold blade into a position to be ejected from the carrier into the type channel, and also to move vertically, whereby it may be brought up into position to receive the type from the mold, and as it retreats toward the type channel to drop down below a level where it might interfere with the die case and parts associated therewith, the combined horizontal reciprocatory and vertical movements being effected by the operating link 247 and inclined guideways in which the carrier itself travels, all as is common in the commercial machines, and as set forth in the patent before referred to.

In the operation of the machines, as heretofore constructed, difficulty has been experienced because of the liability of the movable parts of the type carrier to become broken or injured as well as by reason of injury to the type transferred by the carrier, all due in a large measure to the inertia and momentum of the moving parts, for it will be remembered that the moving parts of the type carrier travel at high

speed while in motion and must be brought to rest quickly at the extremes of their movements.

In accordance with the present invention and contrary to what might be expected, the strength of the moving parts has been increased in so far as their effective operation is concerned by reducing their weight, and the effect of inertia and momentum has been practically eliminated by causing the moving parts to be gradually accelerated during the initial part of their movement and gradually arrested during the final portions of their movements, with a corresponding increase in the speed of movement at intermediate points whereby the total time consumed in the movements is not changed, and as the effective positions of the parts are at the extremes of the movement, the speed of operation of the machine remains the same or may be increased without injury.

Referring particularly to Figs. 2 to 6, it will be seen that the body of the type carrier indicated by the reference number 5 is provided at one end with a slotted head 250 corresponding in all essential particulars to the head 250 of the patent before referred to, and that working in the carrier there is the clamping member which corresponds to the clamping member 251 of the said patent; that is to say, it is provided with clamping jaws 6, which coöperate with the wall of the slot in the head of the carrier for clamping a type while being transferred from the mold to the type channel. The body portion 7 of the clamping member in the present instance is mounted to slide in the body 5 of the carrier, and is provided with a rearward extension 8 terminating in a head or shouldered projection 9 and an extended pin 10, all as shown in Fig. 6. It is adapted to be seated in the body of the carrier behind a face plate 11 by which it is held in place and guided, and the pin 10 is adapted for the reception of a coil spring 12 which is compressed between the shouldered projection or head 9 and an inturned end or shoulder 13 (Fig. 5) on the face plate 11, whereby the clamping member is normally held advanced toward the end of the carrier and in position for its clamping jaws 6 to coöperate with the slotted end or head of the carrier. As is well understood in the operations of these casting machines the type carrier advances into a position for the reception of the type ejected from the mold, and when in such position the clamping member is retracted against the tension of its spring to permit of the entry of the type. In the machines as heretofore constructed, the clamping member was retracted by the coöperation of a projection thereon with a fixed stop or part on the frame of the machine, the posi-

tion of the stop being such that during the advance of the type carrier and as it neared the extreme of its movement, the movement of the clamping member was arrested, and on the return movement with a type in position in the slotted head, the contact of the type with the clamping member inaugurated the movement of the clamping member in unison with the carrier. The movement of the clamping member was therefore in unison with the type carrier, and the inertia and momentum of the clamping member were overcome by contact with unyielding parts.

In accordance with the present invention the difficulties incident to such construction have been overcome by providing a means whereby a differential speed of movement is imparted to the clamping member, in such wise that its movement is gradually inaugurated and gradually arrested, and in the preferred arrangement, illustrated in the drawings, this result is accomplished by the employment of a cam member, which co-
operates with a fixed stop and with a projecting portion of the clamping member. By reference to Fig. 5 it will be seen that a cam lever 14 is pivotally mounted in the body of the carrier and projects upwardly in front of the head or enlargement 9 of the clamping member. It is provided with a curved or cam face 15 for coöperation with the straight face of the head 9 and with a curved or cam face 16 for coöperation with a fixed stop 17. The fixed stop 17 may conveniently be formed as a part of a shoe 18 secured to the frame of the machine at one side of the carrier with the projection extending over the carrier into position to co-
operate with the cam lever 14, prior to and during the time the type carrier is at the forward extreme of its movement, thereby causing the clamping member to have a relative rearward movement which movement will, owing to the action of the cam lever, be gradually inaugurated as the carrier moves forwardly and gradually arrested as the carrier moves rearwardly. Such movement of the clamping member is of course timed as heretofore to clamp the type immediately after the carrier begins its reverse movement.

The type support which is the part employed for maintaining the type in upright position in the slotted head, before it is clamped, by the clamping member, as heretofore constructed, was open to some of the objections referred to in connection with the clamping member, that is to say, because of its weight and the fact that it was started and stopped in its movement relative to the type carrier with a sudden or hammer-like action, it was liable to be broken, or cause excessive wear and noise. In the present arrangement the type support which corre-

sponds to the support 255 of the patent before referred to is formed by a spring blade 18, the extremity of which is preferably widened vertically of the carrier and made of considerable thickness by bending its end 19 reversely as shown in Fig. 6. The base of the blade is rigidly secured to the forwardly projecting end 20 of a slide 21. The slide 21 is provided with a guideway, one 10 end wall 22 of which forms a shoulder for coöperation with an operating lever, as will be presently explained. Working in the guideway formed by the slide 21 is a block 23 which forms the coöperating shoulder 15 for the operating lever. This block is formed as a part of a secondary slide 24 having at its rear end a head 25 forming a bearing for a pin 26 mounted in the end of the slide 21. Around the pin and between 20 the slide 21 and the shoulder 25 is a coil spring 27 which by its expansion tends to hold the lock 23 toward the end wall 22 of the slide and serves as a yielding member which will permit the operating lever to 25 advance should the forward movement of the type support be obstructed.

The operating lever in the present instance is pivotally mounted at 27 in a bearing on the upper portion of the type carrier 30 and is provided with a headed projection or arm 28 working between the shoulders on the block 23 and slide respectively, as well illustrated in Fig. 5 of the drawings. The lever is provided with two outwardly 35 curved or flaring arms 28 and 29 preferably located in different planes longitudinally of the carrier and adapted to coöperate with fixed cams or inclines 30 and 31, respectively, which latter are conveniently mounted 40 on a standard 32 fastened to the main frame of the machine, as by screws 33.

The type support is guided in ways formed in the body of the carrier and extends through between lugs 34 on the clamping member so as to occupy, when advanced, a position which will intercept and support the type ejected from the mold by the mold blade, and the cams 30 and 31 are so located with relation to the movement of the 45 type carrier that the said support is advanced into operative position when the type carrier is advanced for the reception of a type and is retracted or drawn out of operative position when the type carrier is 50 in position for the discharge of its type into the type channel, for it will be remembered that the type enters the carrier on one side and is ejected from the carrier on the opposite side by the forward movement of the 55 ejector blade 259. The curvature of the arms 28 and 29 together with the conformation of the fixed cam surfaces 30 and 31, are such that the movements of the type support with relation to the carrier are inaugured and arrested gradually, thus

eliminating from these parts any hammer-like action or shock incident to their inertia or momentum.

A type carrier constructed as herein described, may be made with its working parts 5 much lighter than heretofore, and at the same time ample strength and rigidity maintained to insure a proper action without wear or injurious shock or strain. Inasmuch as the working parts are arrested and their movements inaugurated gradually with relation to the movement of the type carrier itself, the speed of operation may be very materially augmented, which feature is an important one in connection with type casting machines of the character to which the invention relates, especially when such machines embody means whereby the freezing of the type metal may be effected with extreme rapidity or where the type bodies are 85 of small dimension and the machine may as a consequence be run at high speed.

From Fig. 5 it will be observed that the fixed abutment 17 is located immediately above an inclined surface of the carrier and it may be here remarked that such inclined surface is in practice preferably an extension of the surface of the inclined rib or guide by which the carrier is guided in its diagonal movement into and out of position 90 for receiving the type from the type mold. The said rib is shown in Figs. 2 and 4 at 40, and its inclination is indicated in Fig. 5 by the dotted line 41.

What we claim is:

1. In a type casting machine, the combination with a mold and means for ejecting the type from the mold, of a reciprocatory type carrier for receiving and transferring the ejected type, a member for clamping the type in the carrier and means for imparting a differential speed of movement to the clamping member whereby shock due to inertia and momentum will be reduced.

2. In a type casting machine, the combination with a mold and means for ejecting the type from the mold, of a reciprocatory type carrier for receiving and transferring the ejected type, a type clamping member mounted in the carrier, and means for imparting a differential speed of movement to the clamping member, whereby shocks due to inertia and momentum will be reduced.

3. In a type casting machine, the combination with a mold and means for ejecting the type from the mold, of a reciprocatory type carrier for receiving and transferring the ejected type, a type clamping member slidably mounted in the carrier, and means for inaugurating and arresting the movements of the clamping member at a speed less than that of the carrier.

4. In a type casting machine, the combination with a mold and means for ejecting the type from the mold, of a reciprocatory

type carrier for receiving and transferring the ejected type, a spring-pressed type clamping member mounted in the carrier and means for retracting said clamping member with relation to the carrier and at a differential speed.

5. A type carrier for type casting machines, embodying a body having a type channel therein, one wall of which forms a type clamping surface, a coöperating clamping member mounted in the carrier and means for moving the clamping member with relation to the carrier at a differential speed.

10. 6. A type carrier for type casting machines embodying a body having a type channel therein, one wall of which forms a type clamping surface, a coöperating clamping member movably mounted in the carrier, and a cam member coöperating with the clamping member to impart a differential movement thereto.

15. 7. A type carrier for type casting machines embodying a body having a type channel therein, one wall of which forms a type clamping surface, a coöperating clamping member movably mounted in the carrier, and a pivoted member having a cam surface coöperating with the clamping member to impart a differential movement thereto.

20. 8. A type carrier for type casting machines embodying a body having a type channel therein, one wall of which forms a type clamping surface, a coöperating clamping member movably mounted in the carrier, a cam member pivotally mounted on the carrier and having a cam surface coöperating with the clamping member and a 25 reversely arranged cam surface for coöperation with a fixed abutment whereby the cam member will be operated to impart a differential movement to the clamping member with respect to the carrier.

30. 45. 9. A type carrier for type casting machines, embodying a body having a type channel therein and means for clamping the type in the channel, and a type support movably mounted in the carrier with means for

50 moving the support with relation to the carrier at a speed which gradually increases and diminishes toward the extremes of the movement.

10. A type carrier for type casting machines embodying a body portion having a type channel therein, and means for clamping the type in the channel and a type support movably mounted in the carrier with means for moving the support with relation to the carrier at a speed which gradually increases and diminishes toward the extremes of the movement, such means embodying oppositely disposed inclines and a coöperating lever member.

15. 11. In a type casting machine, the combination with a mold, and means for ejecting the type from the mold, of a reciprocatory type carrier for receiving and transferring the ejected type, a member for clamping the type in the carrier, a member for supporting the type in the carrier while being clamped, and means for imparting differential movements to the clamping and supporting members with relation to the carrier whereby shocks due to inertia and momentum will be 75 reduced.

20. 12. In a type casting machine, the combination with a mold, and means for ejecting the type from the mold, of a reciprocatory type carrier for receiving and transferring the ejected type, means for clamping the type in the carrier while being transferred, a type support movable with relation to the carrier into and out of position for supporting the type while being clamped, an operating lever for said support having divergent operating arms and fixed cams with which said arms coöperate for gradually inaugurating and arresting the movements of the support with relation to the carrier during the movements of the latter.

JOHN SELLERS BANCROFT.
